UNITED STATES PATENT OFFICE.

AUGUST C. RADER, OF UPPER MONTCLAIR, NEW JERSEY.

CURTAIN-FIXTURE.

1,113,690.

Specification of Letters Patent.

Patented Oct. 13, 1914.

Application filed January 5, 1914. Serial No. 810,437.

To all whom it may concern:

Be it known that I, AUGUST C. RADER, a citizen of the United States, residing at Upper Montclair, in the county of Essex 5 and State of New Jersey, have invented a new and useful Curtain-Fixture, of which the following is a specification.

This invention relates to curtain fixtures particularly designed for use in connection 10 with curtains such as used in railway cars.

One of the objects of the invention is to provide a fixture of this character which is cheap to manufacture and which utilizes 15 guide engaging rollers supported in a novel manner whereby said rollers are free to shift inwardly, upwardly and downwardly relative to the curtain, each roller being formed with a support which constitutes part of a spring operating to hold the roller normally projected outwardly to active or guide 20 engaging position.

Curtain fixtures such as heretofore devised have been found objectionable for the reason that they do not avoid creeping such 25 as results from the constant swaying or vibration of the car structure. The present device has been designed to overcome the creeping action of fixtures such as heretofore constructed.

30 With the foregoing and other objects in view which will appear as the description proceeds, the invention resides in the combination and arrangement of parts and in the details of construction hereinafter described 35 and claimed, it being understood that changes in the precise embodiment of the invention herein disclosed, can be made within the scope of what is claimed, without departing from the spirit of the invention.

40 In the accompanying drawings the preferred form of the invention has been shown.

In said drawings:—Figure 1 is a view partly in front elevation and partly in section of a portion of a curtain and of the fixture applied thereto. Fig. 2 is a front elevation of a portion of the fixture and showing, in full lines, one position of the roller relative to its supporting structure, 50 and, in dotted lines, another position of the roller. Fig. 3 is a plan view of the structure shown in Fig. 2. Fig. 4 is an enlarged section on line A—B Fig. 2.

55 Referring to the figures by characters of reference 1 designates a tube adapted to be connected to one end of a curtain 2, this

tube having its end portions interiorly screw threaded for the reception of a stem 3. This stem is preferably made up of two springs riveted or otherwise secured together and 60 having their edge portions threaded as shown so as to engage the interior of the tube 1 and also to engage a lock nut 4 adapted to bear against the end of the tube. The outer ends of the springs making up 65 the stem diverge, as shown at 5, one of these diverging portions merging into a shoe 6 having side retaining fingers 7. The other diverging portion 5 merges into a shoe 8, 70 having side retaining fingers 9 while extending from the middle portion of the shoe 8 is an arcuate tongue 10 which is turned under the shoe 6 and lies close thereto. A roller 11 has its periphery engaged by the shoes 6 and 8 while the fingers 7 and 9 lap 75 the sides of the roller. This roller is formed with a deep annular groove 12 forming a central core 13 and the arcuate tongue 10 extends into this groove and partly around the core 13 so as to limit the movement of 80 the roller outwardly away from the shoes 6 and 8 and to hold said shoes constantly in contact with the roller.

In using the structure herein described, the stems 3 are adjusted toward or from 85 each other so that the distance between the outer extremities of the two rollers 12 will be slightly greater than the distance between the faces of the guides to be engaged thereby. When the curtain is to be applied 90 to a window casing, the rollers 12 are pushed toward each other so as to press against the shoes 6 and 8 and spread apart the extensions 5 of the spring strips and, as soon as the rollers have been brought to positions 95 within the casing, they are released, whereupon the springs 5 and shoes 6 and 8 will shift the rollers outwardly against the inner walls or surfaces of the guide grooves 100 in the casing. Thus the cores 13 will not contact with the tongue 10 but, on the contrary, will be spaced therefrom as indicated by dotted lines in Fig. 1. Consequently, the diverging portions 5 of the springs and the shoes 6 and 8 will exert a 105 constant outward pressure against the rollers so as to cause them to bind tightly against the casing under all conditions and, should the car be caused to sway or vibrate, any tendency of the fixture and curtain to 110 creep upwardly in the casing will be avoided inasmuch as each roller will be free to shift

upwardly and downwardly as well as inwardly relative to its supporting means and without changing the position of the curtain. The retaining fingers 7 and 9 operate to hold the rollers against lateral displacement relative to their supports.

What is claimed is:—

1. A curtain fixture including a guide engaging roller, means for limiting the movement of the roller outwardly to active position, said roller being movable upwardly, downwardly and inwardly relative to said limiting means, and yielding means for retarding said upward, inward and downward movement of the roller relative to said limiting means.

2. A curtain fixture including a guide engaging roller, and means for connecting said roller to a curtain, said means including roller engaging springs for pressing the roller outwardly normally to its active position, and means for limiting such outward movement of the roller, said means being integral.

3. A curtain fixture including a stem, said stem having integral diverging springs formed with shoes, a roller having its periphery contacted by the shoes, said roller being formed with a peripheral groove, and means extending from one of the springs and into the groove for limiting the movement of the roller away from the shoes.

4. A curtain fixture including a stem, said stem having integral diverging springs formed with shoes, a roller having its periphery contacted by the shoes, said roller being formed with a peripheral groove, and an arcuate tongue extending from one of the shoes and into the groove for limiting the movement of the roller away from the shoes.

5. A curtain fixture including a stem, said stem having integral diverging springs formed with shoes, a roller having its periphery contacted by the shoes, said roller

being formed with a peripheral groove, an arcuate tongue extending from one of the shoes and into the groove for limiting the movement of the roller away from the 50 shoes, and means for varying the pressure of the springs upon the roller.

6. A curtain fixture including a stem, said stem having integral diverging springs formed with shoes, a roller having its periphery contacted by the shoes, said roller being formed with a peripheral groove, an arcuate tongue extending from one of the 55 shoes and into the groove for limiting the movement of the roller away from the 60 shoes, and side retaining fingers upon the sides and lapping the sides of the roller.

7. A curtain fixture including spring supported shoes, a roller having its periphery engaged thereby, said roller being formed 65 with an annular groove, and means integral with one of the shoes for extending into the groove to limit the movement of the roller away from the shoes.

8. A curtain fixture including spring supported shoes, a roller having an annular groove, an arcuate tongue extending from one of the shoes and into the roller for holding the periphery of the roller pressed 70 normally against the shoes, and means for 75 varying the pressure of the shoes upon the roller.

9. A curtain fixture including spring supported shoes, a roller having an annular groove, an arcuate tongue extending from 80 one of the shoes and into the roller for holding the periphery of the roller pressed normally against the shoes, and side retaining means extending from the shoes and 85 lapping the sides of the roller.

In testimony that I claim the foregoing as my own, I have hereto affixed my signature in the presence of two witnesses.

AUGUST C. RADER.
